UNITED STATES PATENT OFFICE.

FRANCIS H. WILLIAMS, OF SYRACUSE, NEW YORK.

CHAIN-SHELL.

SPECIFICATION forming part of Letters Patent No. 325,300, dated September 1, 1885.

Application filed June 15, 1885. (No model.)

To all whom it may concern:

Be it known that I, FRANCIS H. WILLIAMS, of Syracuse, county of Onondaga, State of New York, a citizen of the United States, have 5 invented certain new and useful Improvements in Projectiles, which I call a "Chain-Shell," consisting of two hollow shells filled with an explosive compound that explodes by concussion, and connected together by a chain 10 that can be propelled from any ordinary gun without danger of exploding the projectile by the force of the charge in the gun by which the explosive shell is projected, so that dynamite or other highly-explosive shell can be 15 shot off with safety from the gun like any ordinary projectile, and the shells so adjusted that two explosions will be made on impact with the object fired at. I attain these results by the devices illustrated in the drawings, in which—

Figure 1 is a longitudinal view of the shell ready to be placed in the gun. Fig. 2 is a sectional view of the shell; Fig. 3, a sectional view of a hollow elastic cylinder with a chain 25 drawn through it, the chain having a snap-hook on each end of it.

In the employment of my new device the charge of powder, gun-cotton, or other proper material is like that heretofore used in any 30 ordnance for throwing shot or shell. The explosive shells B B may be formed in any known way or shape to contain the explosive material with which it is charged. I would make one of the shells B B of more weight

than the other, the diameter of each to be the 35 same, for the purpose of giving a more direct flight to the object fired at, and to cause two explosions to be made, by reason of the heavier shell striking first on the object fired at.

I make no claim of novelty to either of these 40 elements B B C, which may be so varied as to suit the purpose of the gunner. Between these elements B B and around the element C my invention is placed. It consists of a short cylinder, A, formed of any flexible or yielding material to surround the chain C to act as a buffer, sabot, or cushion between the shells B B. The mode of forming the cylinder A can be varied, as well as its length, to suit the purpose for which it is intended, it being 45 made of sufficient length, elasticity, and resistance to suit the charge, heavy or light, and a shell for long or short range, the cushion, sabot, or buffer A being adapted thereto.

I am aware that rubber, spring, fibrous, and 50 analogous buffers have been used as a component part of shells. These I do not claim.

Having thus described my invention, I claim—

The combination of the explosive shells B 60 B, the chain C, uniting them, and the tubular elastic buffer surrounding the chains, substantially as described.

FRANCIS H. WILLIAMS.
